Mario Randon
INVENTOR
BY *Victor J. Evans*
ATTORNEY

UNITED STATES PATENT OFFICE.

MARIO RANDON, OF STAFFORD SPRINGS, CONNECTICUT.

REGISTER.

Application filed October 11, 1921. Serial No. 506,977.

To all whom it may concern:

Be it known that I, MARIO RANDON, a citizen of Italy, residing at Stafford Springs, in the county of Tolland and State 5 of Connecticut, have invented new and useful Improvements in Registers, of which the following is a specification.

My present invention has reference to a coin registering device which is primarily 10 devised for use by street car conductors for registering five cent fares, however its use is not limited for this purpose only.

My primary object is to produce a device 15 of this character in which the conductor, by observing the numbers on the registering disks of the improvement may accurately determine the amount of coins or tokens received from passengers and be thus materially assisted in making proper returns 20 to the office after trips.

A further object is to produce a coin registering device which includes a coin chute and registering disks and which has an ejector for moving a coin out of the chute, 25 while means is provided and which are engaged by the coin during the ejection thereof for revolving the disks so that the coins received will be properly registered upon each actuation of the ejector.

30 The foregoing, and other objects which will appear as the nature of the invention is better understood, may be accomplished by a construction, combination and operative association of parts, such as is disclosed by the drawings which accompany 35 and which form part of this specification.

In the drawings:—

Figure 1 is an elevation of the improvement.

40 Figure 2 is a sectional view on the line 2—2 of Figure 1.

Figure 3 is a sectional view on the line 3—3 of Figure 2, the coin being arranged in the chute prior to the ejection therefrom.

45 Figure 4 is a substantially similar view showing the coin in the process of being ejected and the manner in which the same influences the means for rotating the registering disks.

50 Figure 5 is a sectional view through the casing showing the registering disks.

Figure 6 is a detail view of the registering disks showing the means for rotating one disk from the rotation of the others 55 through the medium of a train of gears.

Figure 7 is a detail view showing a portion of the disk revolving mechanism.

Figure 8 is a sectional view taken on line 8—8 of Figure 3.

Referring now to the drawings in detail, 60 the numeral 1 designates a casing of a size and shape which renders the same convenient for support from the belt of the conductor of a street car or other line.

The casing 1 has its outer face provided 65 with any desired number of spaced substantially rectangular openings 2. These openings may be covered by transparent plates, and to the rear of each of the openings there is a registering disk. The disks 3 have 70 each imprinted upon their outer faces numerals from 1 to 0, the said disks being also of the usual construction employed in such devices. The first disk 3' has im-

printed upon its face numerals from 0 to 75 95 and is provided with a tooth or finger 3'' which, on the complete turning thereof will engage with the depressions or lugs on the second disk to cause the second disk to turn one-tenth of a revolution upon the complete revolution of the first disk, the second disk likewise engaging the third disk and the third disk engaging the last disk in a similar manner. In this manner, four figures on the respective disks will be dis-

cernible through the openings 2. The first opening discloses the number of fares passed through the device when the number there- 80 of is below a hundred, the next below a thousand, the next number below ten thou- 85 sand and the last below a hundred thousand.

In other words the first disk registers fares from one to ninety-nine, the next from one hundred to nine hundred and ninety-nine, the next from one thousand to nine hundred 90 and ninety-nine thousand, and the next from ten thousand to ninety-nine thousand nine

95 hundred and ninety-nine. The total of all the numbers in the openings must be read backwards, that is if a 1 shows through the last opening, a 2 through the next, a 3 through the next and a 4 through the first opening, the amount of fares that have 100 passed through the device are twelve thou-

sand three hundred and forty.

105 In the casing there is a vertically disposed coin chute 4, the mouth of the chute being, of course, arranged at the top of the casing. The chute, at its lower end is provided with a longitudinal passage 5, which is in com-

munication as at 5' with a lower passage, that is in the nature of a coin delivery chute and which is indicated by the numeral 6. The outlet 7 of the delivery chute may communicate with a suitable coin box or, if desired, the said outlet may be arranged at the bottom of the casing so that the coins may be delivered into the hand of the conductor.

10 Adjacent the wall of passage 5 there is normally arranged the coin contacting flange or head 8 of the ejector. The main or body portion 9 of the ejector is of a size to be snugly received within a portion of the 15 passage 5 which acts as a guide therefor. The body 9 has one end projecting beyond the inner end of the passage and has secured or may be integrally formed at its opposite end with a spring finger 10, the finger passing through a slot 11 in the outer face of the passage, and being connected to the head 8. The spring normally forces the head 8 against the inner wall of the passage 5.

15 The referred to projecting end of the 20 body 9 of the ejector has a vertically disposed slot 12 therethrough, and in this slot there is received a pin 13 which projects laterally from one end of a bell crank lever 14, the fulcrum or pivot of the said lever, indicated by the numeral 15, being mounted in the casing or in the supporting frame 16 for the disks 3. The second arm of the bell 25 crank lever has attached thereto a spring 17, the opposite end of the said spring being secured to the inner wall of the delivery chute 6. The spring, of course, influences the bell crank lever to cause the pin on the latter to move in the slot of the ejector to influence the latter to bring the head thereof in a line with the outer end wall of the coin receiving chute 4, so that a coin may be freely received in the chute and be disposed in the path of contact with the said head of the ejector.

30 40 The substantially rectangular box-like portion of the device which I have referred to as the passage 5 has its upper wall at its juncture with the coin receiving chute 4 provided with an elongated opening 18, and 45 in this opening there is received the offset end or finger 19 of a rod 20. The finger is normally retained in the opening 18 through the medium of a spring 21 which contacts with the rod 20, the said spring being secured to the supporting frame for the disks. 50 The opposite end of the rod 20 is pivotally connected, as at 21' to a wheel 22 that has its shaft 23 journaled in suitable bearings in the disk supporting frame. On the shaft 60 23 there is an arm 24 which has its free end widened and provided with spaced teeth 25 and 25' respectively. The teeth are designed to engage with a ratchet wheel 26 secured upon the inner face of the first disk 65 3' as clearly shown in Figure 7 of the draw-

ings. The tooth 25' together with its attaching portion to the arm 24 is resilient and is adapted to turn the ratchet wheel 26 as will be readily apparent, while the tooth 25 acts as a stop means for the wheel. Suitable 70 means 27 are provided for holding the disks from turning, except in one direction. This means 27 is in the nature of a leaf spring extending from the upper wall of the casing and having its lower end engaging the teeth of the ratchet wheel 26 in its rotation, the ratchet wheel being secured to the disks 3' which is associated with the disks 3 through the medium of a train of gears, thereby all the disks are prevented from turning by the 80 leaf spring engaging the tooth of the gear 26, except with the cammed surfaces of the teeth of said gear. The disks cannot be returned to the zero marks by the conductor between trips or after the day's work, as it is necessary that the conductor make proper note of the figures indicated on the disk after one run or after the day's run, and count therefrom the coins received in the subsequent run.

85 To the outer end of the bell crank lever there is pivotally connected a rod 29 that passes through a suitable opening in the top of the casing 1, the said rod having its outer end provided with a head 30.

90 The operation may be briefly described as follows:

95 A coin is deposited in the coin receiving chute 4 and is, of course, received between the head 8 of the ejector and the finger 19 of the disk operating rod 20. A pull is exerted on the head 30 of the rod 29 which turns the bell crank lever causing the pin 13 in the slot 12 of the ejector to move the 100 said ejector longitudinally to bring the head thereof inwardly of the passage 5. Such movement of the ejector causes the coin to be brought forcibly against the finger 19 of the rod 20, moving the said rod longitudinally and thus turning the wheel 22 causing 105 the toothed end 25' of the arm 24 on the shaft 23 to turn the ratchet wheel 26 one-twentieth of a revolution, and likewise influencing the first disk 3'. The spring 21 which engages the rod 20 will return the 110 rod to initial position and the spring 17 connected to the bell crank lever will return the operating rod 29 and the ejector to initial position.

115 120 It is thought that the foregoing description, when taken in connection with the drawings will fully set forth the construction, operation and advantages of the improvement to those skilled in the art to which such inventions relate and therefore further detailed description will not be attempted. It is, however, thought necessary to state that the showing and description refer only to a satisfactory embodiment of the improvement as it now appears to me and that 125 130

I am entitled to make all such changes therefrom as fall within the scope of what is claimed.

Having described the invention, I
5 claim:--

A coin register of the character described comprising a casing, a coin chute having a lateral extending coin passage at the bottom thereof, a coin outlet chute arranged at the bottom of said casing and communicating with the coin passage, registering disks rotatably mounted in the casing, an ejector comprising a head, a body and a spring

finger connection between the head and body, said ejector being movable through 15 the coin receiving passage, said spring finger being adapted to retain said head in operative engagement with a coin, spring means influencing the coin ejector, means for moving the ejector partly through the passage 20 to deliver the coin therefrom to the coin receiving chute and means contacted by the coin when so moved for revolving the registering disks.

In testimony whereof I affix my signature.

MARIO RANDON.
